STEAM GENERATOR AND DRAFT CONTROL FOR LOCOMOTIVE FIRE BOXES

Application filed July 10, 1928. Serial No. 291,621.

This invention relates to an improvement in locomotive fire boxes, and has for its object, broadly, to provide a water container which will operate to advantage as a steam generator and draft control to thereby cause more effective combustion and a material saving in fuel.

One of the specific objects is to provide such a mounting for the container that leakage will not occur from expansion caused by excessive heat.

Another object is to provide such a mounting for the conduits of the container in the water spaces that flushing may be readily accomplished.

The invention includes parts which may be conveniently assembled in the fire box, and is intended to operate as a substitute for the brick arch now generally used in the fire boxes of locomotives, but to provide a more effective and convenient means than heretofore provided.

With the foregoing objects in view and others to be mentioned the invention presents a new and useful construction, combination and arrangement of parts as described herein and claimed and as shown in the accompanying drawing, it being understood that changes may be made in form, size, proportion of parts and minor details, said changes being determined by the scope of the invention as claimed.

In the drawing, Fig. 1 is a view in longitudinal section through the fire box showing the water container or steam generator mounted therein and in longitudinal section. Fig. 2 is a sectional view on line 2-2 of Fig. 1. Fig. 3 is a sectional view showing one of the water spaces in section to illustrate the preferred mounting of a water conduit, the view being on an enlarged scale. Fig. 4 is a detail view illustrating one of the holder-edges for supporting the water container. Fig. 5 is a side view of one of the sleeves used for the mounting of a conduit.

Referring now to the drawing for a more particular description, the invention is shown and described in connection with the fire box 6, the combustion chamber 7 in communication therewith and the water spaces 8 which

are disposed at the sides and ends of the fire box.

The invention consists, in part, of a water container 9 adapted to be supported above the ash pit at a suitable distance upon the holder-ledges 10 which are provided for the inner wall 11 at the respective sides of the fire box.

By referring to Fig. 4 of the drawing it will be seen that a ledge 10 consists of a metallic plate 12 curved outwardly to provide the ledge and a water pocket 13, an aperture 14 being formed in the wall 11 to permit water to fill said receptacle so that the holder-ledge will not become injured by heat.

Referring to Fig. 2 of the drawing it will be seen that the opposed sides or edges of the container 9 do not normally engage the walls 11 of the fire box while supported by the ledges 10, this feature being of importance since the container has a greater or lesser degree of expansion resulting from heat, and by this construction injury to the container 9 and walls 11 is avoided.

In order that the water may circulate freely through the container 9 for a communication with the water spaces, and that the container will not become injured by expansion to excessive heat in the fire box, and that leakage will not occur we provide conduits 15 and a particular mounting therefor to be described, said conduits extending from the front and rear ends of the container and providing passageways from the container to the water spaces 8.

Any suitable number of conduits 15 may be provided, and they may have any suitable mounting of their respective ends which will not result in leakage. The form of the conduits is circular in cross-section and preferably, each conduit has a threaded terminal 16 for a mounting in an end of the container, the opposite end of each tubular conduit being slidably mounted in a packing-element 17, best shown in Fig. 3.

Numerals 18 indicate sleeves each adapted to be mounted in an aperture 19 formed in the outer wall 20 and inner wall 11 of a water space 8, as best shown in Fig. 3 of the drawing, one end of each sleeve 18 being threaded

as indicated at 21 for a threaded connection with the inner wall 11 of the water space.

Numeral 22 indicates an annular housing-sleeve for containing the packing 17, its hollow shank which receives a conduit 15 having a threaded connection, indicated at 23, in an end of the sleeve 18.

Numeral 24 indicates a screw-cap which is mounted upon the inner end of the annular housing for compressing the packing 17.

Numeral 25 indicates a second screw-cap for closing the outer end of the sleeve 18, the threaded connection for this cap being upon the projection 26 of the annular plate or collar 27 which is mounted upon the outer wall 20 of a water space, a packing-ring 28 being employed and engaging the ends of the sleeve 18 and projection 26.

Numerals 29 indicate apertures which are provided in the sides of the sleeve 18 which permit a movement of water in the water space through said sleeve.

As shown and described it will be seen that a fluid-tight construction is provided, and no leakage of water to the fire box from the sleeves 18 or conduits 15 will occur. In operation, the container and conduits, regardless of expansion, will not become injured since the conduits may have the sliding movements mentioned in the sleeves 18. The packing 17 will be protected from injury since the water in the sleeve will modify its temperature, its only exposure being the heated water moving through the sleeves 18 from the water spaces.

According to the construction described, the outer ends of all the conduits are slidingly mounted, but as is obvious, the conduits at one of the ends of the container could be mounted stationary in the walls of a water space, and operation would be effective to permit expansion without injury.

It will be noted that the upper side of the container 9 is of convex form its lower side being concave, and on account of this form the gases or a fair proportion thereof will be detained and consumed in the fire box instead of being carried therefrom by suction, the object in view, being to utilize a greater proportion and prevent the waste of fuel to better advantage than usual. However, in the present instance we do not wish to limit ourselves to the shape of the water container nor to the inclination in the fire box, nor to the inclination of the conduits leading from the container to the water spaces.

It will be seen that the water container 9 may be conveniently flushed and that the parts may be readily assembled. After the screw-cap 25 has been removed all parts within a sleeve 18 are accessible, and if new packing 17 is required, the screw-cap 24 may be removed for changing the packing.

We claim as our invention,—

In a steam generator and draft control for a locomotive fire box having walls composed

of sheets with water compartments therebetween, a water container in the fire box, conduits extending from the ends of said water container, sleeves threaded in the inner sheets of the walls extending across the space between the two sheets and extending outwardly beyond the outer sheet, said sleeves having openings therein communicating with the water spaces of the walls, a packing box held within each sleeve and slidably receiving one of the conduits, a collar received about the projecting end of the sleeve and affixed to the outer sheet, and a cap removably mounted upon said collar and acting to close the outer end of the sleeve.

In testimony whereof we have affixed our signatures.

JOHN J. REARDON.
CHARLES T. CHAKA.
